UNITED STATES PATENT OFFICE.

FORREST NOTT PALMER, OF ATLANTA, GEORGIA.

BED STRUCTURE.

1,160,442.

Specification of Letters Patent. Patented Nov. 16, 1915.

Application filed August 18, 1914. Serial No. 857,360.

To all whom it may concern:

Be it known that I, FORREST NOTT PALMER, a citizen of the United States, residing at Atlanta, in the county of Fulton and State of Georgia, have invented certain new and useful Improvements in Bed Structures, of which the following is a specification, reference being had therein to the accompanying drawing.

10 This invention relates to table beds.

The object is to provide a combined table and bed structure of ample rigidity and strength and, yet, exceedingly attractive as an article of furniture.

15 A further object is to provide a structure of the kind specified, which shall include a plurality of portions and instrumentalities, each adapted to be connected to an adjacent portion or instrumentality whereby they 20 may all be conveniently positioned and operated without the necessity of employing tools, etc.

A still further object is to provide a structure which comprises a plurality of portions 25 but which are all self-contained and so related as to be, in part at least, automatic in their movement when being positioned to convert the table into a bed structure.

Still another object within the contemplation of the invention is so to construct and relate the parts that the structure will sustain the required weight, as a bed, and yet be foldable so that the elements of the bed structure will be housed and out of view.

35 The invention in general seeks to provide a combined bed and table structure which is ornamental in appearance and yet which will, in practical use, possess a high degree of strength and durability and which, structurally considered, will be of the greatest simplicity.

Other objects and advantages will in part be obvious from the annexed drawings and will also be in part pointed out in the following description.

45 The invention resides broadly in the features of construction, combination of elements, and arrangement of parts, and in the various relative aggroupments thereof, all 50 as will be exemplified in the construction hereinafter set forth, and the scope of application of which will be indicated in the claims hereto appended.

In the accompanying drawings forming a 55 part of this disclosure, a possible utilization of the invention is illustrated; but it is to be

understood that the drawings are merely illustrative and that other possible embodiments, employing the underlying principles of the invention, fall within the spirit there- 60 of and the objects contemplated thereby.

In these drawings: Figure 1 is a view in perspective of a combined table and bed, constructed in accordance with my invention, in closed position; Fig. 2 is a view in 65 vertical transverse section of the same, in open position; Fig. 3 is a similar view, showing the same closed; Fig. 4 is a view in plan of the structure, in open position; Fig. 5 is a fragmentary view, in vertical section, 70 showing one of the top-portions, a section of one of the side-portions, and one of the spring-positioning members, all in closed position; Fig. 6 is a similar view of these parts in open position; and Fig. 7 is a frag- 75 mentary view of a section of one of the spring-positioning members as mounted on one of the top-portions.

Referring to the drawings, it will be noted that the reference-character 1 designates, 80 generally, the base-portion which, in this instance, includes a horizontal piece suitably secured to the inner walls of two up-standing end-portions or uprights 2, 2 of appropriate form and dimensions. Relatively, the base and two end-portions are 85 rigidly secured together and constitute the supporting media of the structure.

Spaced apart and pivoted at their edges to the uprights 2 are two side or mattress-sustaining portions 3, 3. Normally, these portions are upright and occupy a position at right-angles to the end-portions 2. Being disposed on an axis, indicated at 4, intermediate of their edges, each portion is 95 adapted to be independently rocked on its respective axis into a horizontal position and, thus, at substantially right-angles to the normal, as seen in Fig. 2. To sustain these mattress-sustaining portions 3 in horizontal position, means are, of course, provided; and, in this instance, I elect to hinge upon each of these portions a pair of swinging panels 5 preferably made to simulate, or in imitation of, the outer front portion of 100 a drawer. These panels may lie against the outer surface of each of the side-portions or, as shown in this instance, are cut out of the same. The hinges 6 permit them to swing downwardly when the side-portions 3 are 110 disposed in their horizontal position, as shown in Fig. 2. To hold them in normal

position, that is, in the position shown in Fig. 1, a locking-device is provided for each panel, the same consisting, in this instance, of a spring-actuated plunger 7 mounted on the inner face of the side-portion and adapted to engage a hasp or hook 8 carried by the end of the panel. As will presently be explained, these locking devices are adapted to be automatically operated to release the panels so that they may, by gravity, swing on their axes. These panels, constituting legs, support the outer parts of the side-ports. The rocking portions are, of course, sustained also on their pivots 4. It is also desirable to provide for additional support of said rocking or side-ports, adjacent their inner ends. To this end, I provide a manually rotatable member 9, movably attached to the inner wall of each end-portion 2, and having its lower part enlarged to provide a portion-engaging section 10, the shoulder 11 of which is adapted to underlie the lower surfaces of the edge sections of the rocking portions 3. When the rocking portions occupy their horizontal position (as shown in Fig. 2) their proximate edges are quite close together. They are, however, sufficiently spaced to permit the upper section of the member 9 to occupy a position between them so that they may rest upon the said shoulders 11 when the enlarged section thereof is disposed so that its flat side is in parallelism with the wall of the end-portion 2. Whenever, however, the flat side is given a half-turn, it will aline with the space between the proximate ends of the rocking portions to release them and permit them to be rocked into their upright position.

I have now described only those parts of the mattress-supporting structure which include the rocking portions 3 and the various means for supporting these portions in horizontal position. Additional mattress-supporting structure may, however, be provided; and, in this instance, includes two top-ports 12 which, as illustrated, are suitably hinged at the upper ends of the rocking side-ports 3, as shown in Figs. 2 and 3. The axis of each of these top-ports is formed at 13 so that, when said top-portion occupies its horizontal position, one section (12^a) extends beneath the engaging surface of the portion 3 and is thereby sustained.

As shown in Fig. 5, the top-ports 12 normally rest upon the headed end of the plunger 7 of the panel locking device. Whenever the top-portion is rocked on its axis, it releases the plunger and it will, under the action of its spring, move out of the hasp 8 and release the panel so that it will drop down. On the underside of each of these top-ports is a spring-positioning and holding member 14, which (in this in-

stance) has two end-sections 14^a and a side section 14^b and it is open at one side, thus making it a three-sided structure. This member is slideable, and to this end, is mounted at each end in grooved guide-ways 15 70 suitably attached to the top-ports.

Pivots connected to board-runners 3^a of the side-ports 3, and also to the member 14 is a link 16. By means of these links, the members 14 are maintained in proper 75 juxtaposition to the respective ends of the side-members 3.

Suitably mounted on the inner walls of the end-ports 2, near the top thereof, are limit-blocks 17 which serve to limit the closing movements of the side-ports 3, the edges of the runner-boards 3^a abutting against the blocks. Should the leg-panels 5 fail to position themselves when the rocking-ports 3 are rocked on their pivots, and in order, therefore, to relieve said pivots from strain in that event, I may, if desired, provide a safety-device, in the form of a block 18 mounted on the inner wall of each end-portion 2 and in such location that the upper edges of the board-runners 3^a will abut against said blocks and thereby be limited in their movement. Suitably secured in position so as to be sustained by the rocking side-ports 3 are spring-structures 19. The movable members 14 also carry auxiliary spring-structures 20. Upon these spring-structures are multi-part mattresses 21, 21, the part of each section being connected, as by the web 22 of the ticking. To bridge the gap 23 between the auxiliary spring-structure 20 and the main spring-structure 19, a metallic plate 24 is provided and the mattress rests upon this, as shown in Fig. 2.

When the various portions are folded to form a table, a housing 25 is formed between their walls; and in this the mattress is likewise folded and housed, as shown in Fig. 3. If found necessary or desirable, a spring-pressed bar or rod 26 may be provided at the foot of the structure, as on one of the members 14, for the purpose of retaining the bed-clothes.

While I have illustrated my invention as applied to a library table, it is manifest that it may be utilized in connection with other forms of tables.

From the foregoing, it will be perceived that I have succeeded in devising a combined bed and table which is well adapted to achieve the several objects and ends in view. The structure is simple and compact in form and attractive in appearance.

As many changes can be made in the foregoing construction, and many widely different embodiments of the invention can be made without departing from the spirit thereof, it is intended that all matter contained in the foregoing description and

shown in the accompanying drawings shall be interpreted as illustrative and not in any limiting sense. It is also to be understood that the language used in the following 5 claims is intended to cover all of the generic as well the specific features of the invention.

What I claim is:

1. A combined table and bed including in combination, a base-portion, end-portions 10 upstanding therefrom and substantially rigid therewith; side-portions pivoted on the end-portions and tilttable in relation to the base-portion; a top-portion pivoted on one of the side-portions and adapted normally to occupy a position at approximately 15 right-angles thereto and, when said side-portions are rotated on their axes, to lie in a horizontal plane therewith; and sustaining portions attached to and normally 20 lying parallel with certain of the portions and adapted to occupy an upright position when said side-portions are in a horizontal position.

2. A combined table and bed including in combination, a base-portion; end-portions 25 upstanding therefrom and substantially rigid therewith; side-portions pivoted on the end-portions and tilttable in relation to the base-portion; a plurality of top-portions, 30 each pivoted on a side-portion and adapted to occupy an edge-to-edge position relatively to each other and at right-angles to the side-portions, and when they have been rotated on their axes, to lie in a horizontal 35 plane therewith; and sustaining portions attached to and normally lying parallel with certain of the portions and adapted to occupy an upright position when said side-portions are in a horizontal position.

3. A combined table and bed including in combination, a base-portion; end-portions 40 upstanding therefrom and substantially rigid therewith; side-portions pivoted on the end-portions and tilttable in relation to the base-portion; a plurality of top-portions, 45 each pivoted on a side-portion and adapted to occupy an edge-to-edge position relatively to each other and at right-angles to the side-portions, and when they have been rotated on their axes, to lie in a horizontal plane therewith; 50 slideable spring-positioning and holding members mounted on the top-portions; and sustaining portions swingingly attached to and normally lying parallel with certain of the portions and adapted to occupy an upright position when said side-portions are in a horizontal position.

4. A combined table and bed including in combination, a base-portion; end-portions 55 upstanding therefrom and substantially rigid therewith; side-portions pivoted on the end-portions and tilttable in relation to the base-portion; a plurality of top-portions,

each pivoted on a side-portion and adapted to occupy an edge-to-edge position relatively to each other and at right-angles to the side-portions, and when they have been rotated on their axes, to lie in a horizontal plane 70 therewith; slideable, three-sided spring-holding members shiftably carried by said top-portions; and sustaining portions swingingly attached to and normally lying parallel with certain of the portions and adapted 75 to occupy an upright position when said side-portions are in a horizontal position.

5. A combined table and bed including in combination, a base-portion; end-portions 80 upstanding therefrom and substantially rigid therewith; side-portions pivoted on the end-portions and tilttable in relation to the base-portion; a plurality of top-portions, 85 each pivoted on a side-portion and adapted to occupy an edge-to-edge position relatively to each other and at right-angles to the side-portions, and when they have been rotated on their axes, to lie in a horizontal plane 90 therewith; slideable, three-sided spring-holding members shiftably carried by said top-portions; connections between said holding members and the tilttable side-portions; and sustaining portions swingingly attached to and normally lying parallel with certain of the portions and adapted to occupy an upright position when said side-portions are in a horizontal position.

6. A combined table and bed including in combination, a base-portion; end-portions 95 upstanding therefrom and substantially rigid therewith; side-portions pivoted on the end-portions and tilttable in relation to the base-portion; a plurality of top-portions, 100 each pivoted on a side-portion and adapted to occupy an edge-to-edge position relatively to each other and at right-angles to the side-portions, and when they have been rotated on their axes, to lie in a horizontal plane 105 therewith; slideable, three-sided spring-holding members shiftably carried by said top-portions; connections between said holding members and the tilttable side-portions; guide-ways on said top-portions upon which said members have a sliding movement and by which they are retained in sliding position; and sustaining portions swingingly attached to and normally lying parallel with certain of the portions and adapted to occupy an upright position when said side-portions are in a horizontal position.

7. A combined table and bed including in combination, a base-portion; end-portions 110 upstanding therefrom and substantially rigid therewith; side-portions pivoted on the end-portions and tilttable in relation to the base-portion; a plurality of top-portions, 115 each pivoted on a side-portion and adapted to occupy an edge-to-edge position relatively to each other and at right-angles to the side-portions, and when they have been rotated 120

on their axes, to lie in a horizontal plane therewith; slidable, three-sided spring-holding members shiftably carried by said top-portions; connections between said holding members and the tilttable side-portions; guide-ways on said top-portions upon which said members have a sliding movement and by which they are retained in sliding position; and sustaining-portions swingingly attached to and normally lying parallel with certain of the portions and adapted to occupy an upright position when said side-portions are in a horizontal position, and including drawer-simulating panels hinged at one end to the side-portions and each swinging on an axis at right angles to that of each side-portion.

8. A combined table and bed including in combination, a base-portion; end-portions upstanding therefrom and substantially rigid therewith; side-portions pivoted on the end-portions and tilttable in relation to the base-portion; a plurality of top-portions, each pivoted on a side-portion and adapted to occupy an edge-to-edge position relatively to each other and at right-angles to the side-portions and when they have been rotated on their axes, to lie in a horizontal plane therewith; slidable, three-sided spring-holding members shiftably carried by said top-portions; connections between said holding members and the tilttable side-portions; guide-ways on said top-portions upon which said members have a sliding movement and by which they are retained in sliding position; sustaining-portions swingingly attached to and normally lying parallel with certain of the portions and adapted to occupy an upright position when said side-portions are in a horizontal position, and including drawer-simulating panels hinged at one end to the side-portions and each swinging on an axis at right-angles to that of each side-portion; and locking devices for said panels holding them in normal position.

9. A combined table and bed including in combination, a base-portion, end-portions upstanding therefrom and substantially rigid therewith; side-portions pivoted on the end-portions and tilttable in relation to the base-portion; a plurality of top-portions, each pivoted on a side-portion and adapted to occupy an edge-to-edge position relatively to each other and at right-angles to the side-portions, and when they have been rotated on their axes, to lie in a horizontal plane therewith; slidable, three-sided spring-holding members shiftably carried by said top-portions; connections between

said holding members and the tilttable side-portions; guide-ways on said top-portions upon which said members have a sliding movement and by which they are retained in sliding position; sustaining-portions swingingly attached to and normally lying parallel with certain of the portions and adapted to occupy an upright position when said side-portions are in a horizontal position, and including drawer-simulating panels hinged at one end to the side-portions and each swinging on an axis at right-angles to that of each side-portion; and spring-actuated locking devices for said panels holding them in normal position, said devices being automatically releasable by said top-portions.

10. A combined table and bed including in combination, a base-portion; end-portions upstanding therefrom and substantially rigid therewith; side-portions pivoted on the end-portions and tilttable in relation to the base-portion; a top-portion pivoted on one of the side-portions and adapted normally to occupy a position at approximately right-angles thereto and, when said side-portions are rotated on their axes, to lie in a horizontal plane therewith; sustaining portions attached to and normally lying parallel with certain of the portions and adapted to occupy an upright position when said side-portions are in a horizontal position; and means including an engageable member rotatable on a vertical axis for holding said side-portions in horizontal position.

11. A combined table and bed including in combination, a base-portion; end-portions upstanding therefrom and substantially rigid therewith; side-portions pivoted on the end-portions and tilttable in relation to the base-portion; a top-portion pivoted on one of the side-portions and adapted normally to occupy a position at approximately right-angles thereto and, when said side-portions are rotated on their axes, to lie in a horizontal plane therewith; sustaining portions attached to and normally lying parallel with certain of the portions and adapted to occupy an upright position when said side-portions are in a horizontal position; and means carried by the end-portions and engageable by edges of the two side-portions for holding said side-portions when in horizontal position.

In testimony whereof I affix my signature in presence of two witnesses.

FORREST NOTT PALMER.
